UNITED STATES PATENT OFFICE.

EDWARD S. HALSEY, OF LYNN, MASSACHUSETTS, ASSIGNOR TO HALSEY MANUFACTURING CO., OF WILMINGTON, DELAWARE, A CORPORATION OF DELAWARE.

PIPE THERMOSTATIC MOTOR.

1,105,558.

Specification of Letters Patent. Patented July 28, 1914.

Application filed July 12, 1909. Serial No. 507,070.

To all whom it may concern:

Be it known that I, EDWARD S. HALSEY, of Lynn, in the county of Essex and State of Massachusetts, have invented certain new and useful Improvements in Pipe Thermostatic Motors, of which the following is a specification.

In carrying out my invention I employ a small elongated copper tank about a foot long shaped to saddle on and be clamped about a hot water circulating pipe of the system it is intended to regulate; a small quantity of volatile liquid, boiling at about the temperature it is desirable to maintain in the heating system, is contained in said tank and from which the confined pressure is led to an adjacent diaphragm upon which it acts, by a small tube. The diaphragm in turn, through levers and connecting chains, operates the temperature dominating valve or damper so as to cut down or otherwise govern the heating effect.

The object of my invention is to supply a simple, cheap, efficient self-contained regulating unit, as an article of manufacture which can be readily clamped to the circulating pipe of the heating system in a few minutes without the services of a steamfitter or without disturbing the piping.

Referring to the accompanying drawings which illustrate my invention similar letters refer to similar parts throughout the several views in which—

Figures 1 and 3 are respectively a side and a back view of the complete device bound in position about a section of circulation pipe. Fig. 4 is a vertical section of same. Fig. 5 is a plan view looking down from above. Fig. 6 shows the complete device attached to the circulating pipe and controlling the drafts of the hot water heater. While Fig. 7 shows the position in which the device should be applied when used with a horizontal circulation pipe. Fig. 2 shows the back side of the diaphragm chamber detached from the pressure tank showing the arrangement of the compound lever system and damper operating chain which are worked by the movement of said diaphragm. This portion of the device is nearly identical with the thermostatic motor described by my Patent #916,861 of March 30th 1909.

From this brief description it will be seen that my invention is constructed essentially with the pressure tank "T" shaped to

closely fit a circulation pipe "P" of the hot water system, so that it can be rigidly clamped snugly outside said pipe by the wire laced junction "W" in the copper jacket thereby securing a relatively large and intimate contact with the pipe so as to hold nearly a uniform temperature therewith and with the water circulating through it. The pressure from the boiling of the small quantity of volatile liquid confined within said tank is conducted from it at the extreme top by a small copper tube "C" to the bottom extremity to the diaphragm chamber "D" where it exerts its force by dilating the flexible diaphragm wall against the compound lever system which in turn draws on the chain which leads to the dampers, giving a travel of about five inches.

The diaphragm or expansion chamber is securely fixed to the pressure tank through the medium of three feet provided at the extremities of its three-legged cross yoke "Y" which are screwed to the reinforced triangular shaped metal shield "S" which is secured to said tank.

The various volatile liquids which I employ having different boiling points to meet the requirements of different systems to which they may be attached all have a vapor density considerably greater than that of the confined air so that in expanding the volume of air in the pressure tank "T" is raised up and out by the pressure generated by said vapor to the expansion chamber "D" through the small tube "C" leading from the top of said tank to the bottom of said chamber. As the volume of air in said tank is considerably greater than the cubic capacity of said expansion or diaphragm chamber very little of said vapor will be led into said chamber by diffusion with the air and condensed therein. The small tube "C" is designed to lead from the lowest drainage point of said diaphragm chamber so that at the slightest recession any liquid that might accumulate therein will be re-conveyed to the pressure tank.

To make more clear the working parts of the motor, used to illustrate this case, which are minutely described in the patent above referred to, I here give the details: the expansion chamber is constructed by two large, corrugated, dished, flanged, metal, diaphragm disks, the one fitting within and tight up against the other being the thinner

of the two and is the one that is flexed outward when subjected to internal pressure thus constituting the actuating diaphragm. These two disks are hermetically sealed about their periphery by soldering. The rigid cross yoke "Y" is fixed across the face of the diaphragm; pivoted in this frame is bell crank "L" having working engagement with the central stiffening disk "O" of the diaphragm, by means of a friction wheel pivoted in one extremity of said bell crank, while its other extremity makes working engagement with the two inner short arms of the levers "H" and "H" by means of a long slide and rock-pin passing through it. Since filing the application for the patent above referred to I have devised a means of nearly doubling the maximum travel given to the operating ligament "K" by the co-operation of the two connecting rods "J" and "J" and the said levers "H" and "H" by forming the latter with obtuse angles at their fulcrums or point of pivoting to the frame instead of being straight as formerly. So that now an approximate but imperfect equilateral parallelogram is described by the two said levers and connecting rods "J" and "J" in any of the various relative positions they may assume within their maximum travel from an acute angle at the junction of "H" and "J" when the operating ligament is drawn up to the limits of travel to that of an obtuse angle at this point and an acute angle at union of "J" and "J" when said ligament is let out to its full extent.

While my present invention is applicable to any water heating system it is especially designed for tank heaters, for apartment and office buildings where it is important to always have a supply of very hot water and to guard against scalding. In other words between 140° and 150° F. This is rather difficult especially where the water is heated directly with steam or with natural gas, but with my device connected direct to a balanced steam or gas valve it is easily accomplished. I have found chloroform to be very superior for this purpose, it being quite easily freed from all foreign liquids, thus securing a uniform boiling point. It is also stable and uninflammable which is of importance because of insurance while the boiling point 142° F. is just right giving a regulation close to 150°. There is another liquid, silicon chlorid which is uninflammable and has a boiling point of about 140° F. but it is unstable, corrosive and impractical to handle while its cost alone is sufficient to make it absolutely prohibited.

I have discovered that the tendency to buckle and make a popping noise when a normally concaved corrugated metal diaphragm like that shown is flexed or reflexed to a lesser degree than that of its normal

shape can almost completely be overcome by pressing a multiple of transverse or radial creases into said diaphragm, I preferably use 5 or 6 radial creases equally distributed about the periphery as shown in Fig. 2. The object in correspondingly corrugating the front or convex disk the same as the concave diaphragm disk of the expansion chamber is to reduce the content of the chamber to practically nothing when the diaphragm is collapsed.

It will be noted that the disks or walls of the thermostatic expansion chambers are not spherically curved as has heretofore been the usual form of such chambers or diaphragms, but that each consists of two distinct portions, namely a plane circular central portion and a conical encircling portion extending from the edges of the center to the periphery of the chamber, and making a distinct angle with the plane central portion. The elements of the encircling conical portion are substantially straight (disregarding the corrugations which are local irregularities in a general straight radial line) and they may even be concave between the edges of such circular portion and the periphery of the chamber. This description applies to the outer rigid wall of the chamber, and to the inner flexible movable wall when the chamber is collapsed, as shown in Fig. 4, this inner wall being made to correspond with and fit closely against the outer wall when collapsed, as already described. The central portion of the flexible wall is rigidly maintained in a flat condition by the central stiffening disk O. This improvement is of material importance, since by making the outer part of the flexible disk with its radial elements either straight or concave rather than convex, (considered with respect to the outer side of the chamber when the same is collapsed) I secure a much better and more regular and uniform operation of the thermostat. In changing from the collapsed to the distended condition the flexible diaphragm is first flexed near its periphery, because the area and total pressure acting at this portion are greater than the area of the central part and the pressure acting thereon. Therefore the flexible diaphragm bulges from the rigid wall first at the periphery and then gradually toward the center, moving the central part O evenly, uniformly and regularly.

I claim:—

1. A temperature regulator for heaters, comprising, in combination with a conduit through which the heated fluid to be regulated flows, a tank mounted on the conduit, shaped to embrace and make contact over an extended area with the same, said tank containing a volatile liquid, the boiling point of which is near approximately the temperature desired to be maintained, a motor apparatus

consisting of flexible diaphragms nested one within the other and hermetically sealed together at their peripheries, mounted on the tank and normally convexedly distorted 5 away therefrom, a tube leading from the tank and opening into the space between the diaphragms, and motion-transmitting mechanism located between the tank and motor apparatus arranged to be actuated by movement of the inner diaphragm of the latter.

2. In a temperature regulator for a water heating system, an elongated metal pressure tank having a curved wall to closely fit a circulation pipe of the system, said tank 15 having portions extending around to the opposite side of said pipe and having means for clasping the same to said pipe, a flexible operating expansive chamber supported at a distance from said tank, and valve operating mechanism located between said tank 20 and expansive chamber.

3. In a thermostatic motor the following described lever system; to transmit, redirect, and multiply the motion of an actuating 25 diaphragm; a diaphragm; a frame "Y" fixed to said diaphragm; a bell crank "L" pivoted in said frame; two obtusely angular levers "H" and "H" pivoted on said frame one on each side of said bell crank each of 30 said levers having a long outer arm and a short inner arm; one arm of said bell crank engaged with and worked by said diaphragm the other arm of said bell crank engaged with and working the two short inner arms 35 of said obtuse levers; two equal connecting links "J" and "J" hinged together at a common point "K" in junction with an operating ligament said connecting rods being of such length and so pivoted in eyes in 40 the two outer ends of said levers as to form an approximate but imperfect rhombus or equilateral parallelogram described by the levers "H" and "H" and the rods "J" and "J" whereby a maximum travel of said 45 operating ligament may be produced.

4. A thermostatic motor having an elastic, normally flexed corrugated metal diaphragm provided with regularly distributed concentric and substantially radial creases or corrugations, the said diaphragm when not under pressure having its central portion at one side of the plane of its periphery and movable under pressure toward said plane.

5. In a thermostatic motor, an elastic, concave concentrically corrugated metal dia- 55 phragm provided with a plurality of radial creases intersecting the concentric corrugations, the said diaphragm being formed to present a central portion when not subjected to pressure, at one side of the plane of its 60 marginal portion, the said central portion being movable under pressure toward said plane.

6. In a thermostatic motor, an expansion chamber having a fixed corrugated metal 6 disk and a second disk constituting a thin flexible metal diaphragm provided with corrugations, the two disks being in close relationship with their corrugations matching into each other, the central portions of both 70 disks, when not subject to pressure between the two disks, being at one side of the plane of the margins of said disks.

7. A thermostatic motor including a rigid wall and an elastic diaphragm fixed at its 75 periphery, said wall and diaphragm fitting one within another when collapsed and constituting an expansion chamber and the diaphragm being adapted to move at its central part toward and from the rigid wall, said 80 diaphragm having its central part plane and the radii of its outer portion substantially straight from the circumference of the central part of the outer periphery when in its normal position nearest to the fixed 85 wall.

8. In a thermostatic motor, a flexible dia- phragm rigidly secured at its periphery and having its area greater than the plane area 90 surrounded by its fixed periphery, said dia- phragm being movable in response to fluid pressure exerted upon one surface and being so formed and held when in the low pressure position, that its central portion is in a plane 95 at one side of and parallel to that defined by its fixed periphery, said central portion being movable toward said plane of the fixed periphery.

In testimony whereof I have affixed my signature, in presence of two witnesses.
